NORMAN P. FRASER ^{Inventor}

By *Frank H. Smith*

Attorney

UNITED STATES PATENT OFFICE.

NORMAN P. FRASER, OF DETROIT, MICHIGAN.

DESIGN FOR A VENDING-MACHINE.

54,163.

Specification for Design.

Patented Nov. 11, 1919.

Application filed August 4, 1919. Serial No. 315,322. Term of patent 14 years.

To all whom it may concern:

Be it known that I, NORMAN P. FRASER, a citizen of the United States, residing at Detroit, in the county of Wayne and State of Michigan, have invented a new, original, and ornamental Design for a Vending-Machine, of which the following is a specification, reference being had to the accompanying drawing, forming part hereof.

The figure is a front elevation of the vending machine, showing my new design.

I claim,

The ornamental design for a vending machine as shown.

NORMAN P. FRASER.

Witnesses:

KARL H. BUTLER,
ANNA M. DORR.
